UNITED STATES PATENT OFFICE.

WILSON W. BURSON, OF ROCKFORD, ILLINOIS.

STOP-MOTION FOR KNITTING-MACHINES.

1,172,764.

Specification of Letters Patent. Patented Feb. 22, 1916.

Application filed March 22, 1912. Serial No. 685,546

To all whom it may concern:

Be it known that I, WILSON W. BURSON, a citizen of the United States, residing in Rockford, in the county of Winnebago and State of Illinois, have invented a new and useful Improvement in Stop-Motions for Knitting-Machines, of which the following is a specification.

This invention relates to improvements in mechanisms for automatically stopping a machine of the class wherein a continuous thread, yarn or similar material is fed to the machine whenever the thread breaks or whenever, for any reason, the thread or 15 yarn fails to freely and readily come off of its spool or cone.

The object of the invention is to provide a mechanism of the class above described, which shall be sure and positive in operation, sensitive to any abnormal conditions in the feeding of the thread or yarn or other similar material, and one that is applicable to machines using either one or a plurality of threads or yarns, so that the machine will 25 be automatically stopped upon the breaking of one of the threads or upon the failure of any single thread or yarn to unreel freely from its spool or cone, or from any combination of these abnormal conditions.

My invention furthermore consists in the novel construction of parts and devices and in the novel combinations of parts and devices herein shown and described; and more particularly specified in the claims.

In the drawings forming a part of this specification, Figure 1 is an elevation of a knitting machine showing my improvements applied thereto and showing the belt shifter in its vertical position, whereby the 35 driving belt is allowed to remain on the fast pulley of the driving shaft of the machine. Fig. 2 is a plan view of the structure shown in Fig. 1, parts of the automatic stop mechanism being removed and showing in dotted lines the position of the belt shifter when the same has been released by the automatic stop motion to thereby throw the belt onto the idle pulley of the driving shaft. Fig. 3 is a detail plan view of portions of the stopping mechanism. Fig. 4 is a vertical, sectional view of the structure shown in Fig. 3, taken on the line 4—4. Fig. 5 is a detail view, upon an enlarged scale, taken on line 5—5 of Fig. 7, of part of the mechanism. Fig. 6 is a vertical, sectional view, taken on

the line 6—6 of Fig. 4, and Fig. 7 is a sectional view, taken on the line 7—7 of Fig. 4.

In the drawings, I have shown my automatic stop mechanism as applied to a knitting machine 10 of the general type shown 60 in my Patent No. 996059, issued June 27, 1911, wherein the same is driven by a power shaft 11, the same being provided with fast and loose pulleys 12 and 13, and being driven from any suitable source of power, as 65 by means of a belt 14. Mounted in suitable brackets 15 on the frame of the machine is a belt shifting rod 16, the same having a bent end 17, the latter being adapted normally to be held in a horizontal position, as shown in 70 dotted line in Fig. 2, by means of a spring 18 secured to the shaft at one end and to one of the brackets 15 at its other end. When the belt shifter has its bent end 17 in a horizontal plane, as shown in dotted line in Fig. 2, the same will keep the driving belt 14 on the loose pulley 13, thereby stopping the machine. When the machine is running, the belt shifting rod 16 has its end 17 kept 75 in a vertical plane by means of suitable 80 mechanism hereinafter described, said mechanism being operated by means of the thread or yarn 19 which is being fed from the cone 20 to the knitting machine. The end 17 of the belt shifter is normally main- 85 tained in a vertical plane by means of a crank arm 21 secured to one end of the rod 16 to which is pivoted a connecting rod 22, the latter being pivotally connected at its upper end with one end 23 of an operating 90 lever 24, loosely mounted on a shaft 25. The other end 26 of the lever 24 is normally held down by means of an oscillating hub 27, so that it will be understood that the end 23 of the lever 24 is kept raised and thus 95 retains the portion 17 of the belt shifting rod 16 in a vertical plane against the tension of the spring 18. The shaft or arm 25 is adjustably mounted in a sleeve 28, the latter being in turn adjustably mounted on a ver- 100 tical rod or post 29 secured to the machine.

I have shown my automatic stop mechanism in connection with a knitting machine employing two threads, but inasmuch as practically all of the mechanism controlled 105 by each thread is substantially a duplicate of each of the other mechanisms, I shall only describe the mechanism controlled by a single thread, except where a member is used which is common to all the stopping 110

mechanisms. Also mounted on the supporting arm or shaft 25 is a bracket 30, provided at its inner end with a secondary bracket 31, in which are secured the eyes 32 and 33, through which the thread or yarn passes to the knitting mechanism. Each bracket 30 is provided with a plurality of lugs or arms 34, 35 and 36, as indicated more particularly in Fig. 4 of the drawing. Pivotally mounted on each lug or arm 34 is a tension lever 37, the same being provided with an eye at its outer end through which the yarn or thread passes, and the tension of the thread or yarn will normally maintain the outer end of the lever 37 in an approximately constant position, as shown in Fig. 1 of the drawing. This tension lever 37 forms part of a rotatable hub 38, which has formed integrally therewith a lug or projection 39 (see Fig. 5). The arm 34 is furthermore provided with a stop pin 40 to limit the upward movement of the tension lever 37 against the action of the spring 41 secured to a suitable eye 42 at one end, mounted on the bracket 30, and having its opposite end secured to the hub 38.

Pivotally mounted on each extension or arm 36 is a take up lever 43, the same being provided with an eye at its outer end through which the thread or yarn 19 passes, the lever being adapted to be thrown upward by means of a spring 44, secured at one end to the lever 43, and to a suitable stationary finger 45 of the bracket 30. It will be understood that under normal operating conditions, the lever 43 is maintained in the horizontal position, such as shown in full line in Fig. 1, by the tension of the thread or yarn 19 passing through the eye at its outer end to the knitting machine, but that when the thread or yarn breaks, the spring 44 will throw the lever 43 into the position shown in dotted line in Fig. 1. Rotatably mounted in the arms 36 is the shaft 46, to which is secured the hub 27, as by means of a set screw 47, as shown in Fig. 6. The shaft 46 is provided with an extension which is bent so as to form a U having the vertical portion 48, and the upper horizontal portion 49, as shown in Fig. 6. This extension is made long enough so as to include all of the mechanisms for each thread or yarn being fed to the knitting mechanism, so that the operation of the same by any of the individual levers, in a manner as hereinafter described, will rotate the hub 27 and release the lever 24. The hub 27 is provided with a flat face 50, see Fig. 4, which is normally in the position as shown in said figure, but when a thread or yarn breaks, thus releasing the lever 43, the latter will fly up to the position shown in dotted line in Fig. 1, due to the tension of the spring 44, and will engage the upper member 49 of the shaft 46 and thus rotate the hub 27 to a position where

the flat face 50 thereon allows the end 26 of the operating lever 24 to pass by, thereby allowing the opposite end 23 of the lever 24 to go down and rotate the belt shifting rod 16 under the influence of the spring 18.

73

Pivots mounted on each arm or extension 36 is another lever 51, having pivotally connected thereto at its outer end a rod 52, the latter being guided and held in position by means of a staple or loop 53 on the upright 35. The end of the rod 52 is tapered and normally rests on the lug 39 and is held down by the tapered end engaging in the pocket formed between the lug 39 and the hub 38, and thus preventing the lever 51 from being moved under the influence of a spring 54 connected thereto at one end, and to the eye 42. When, for any reason, thread or yarn fails to unreel freely from its cone 20, the tension lever 37 will be pulled down against the action of the spring 41 to the position shown in dotted line in Fig. 1, whereupon the tapered end of the rod 52 will be thrown up over the hub 38 by the lug 39, thereby allowing the lever 51 to move into engagement with the upper extension 49 of the shaft 46, which will operate to rotate the hub 27 to a position where the flat face 50 thereon will allow the end 26 of the lever 24 to pass thereby in a manner similar to that described heretofore. The hub 27 is preferably provided with a handle 55, whereby the same may be manually set so as to retain the end 26 in its normal position.

95

As will be understood, when the lever 24 is re-set by manipulating the handle 55, the rod 52 will also be simultaneously set in the notch 39.

100

From the foregoing description, it will be apparent that if any thread or yarn being fed breaks, the corresponding take up lever 43 will be released and will fly upward and allow the lever 24 to be released, and thus shift the belt 14 onto the idle pulley 13. If, on the other hand, any thread fails to properly come off from its spool or cone, its corresponding tension lever 37 will be pulled down and will in turn release the lever 24 in the manner as hereinbefore described.

105

I have shown my improvements as applied to a knitting machine, but it will be understood that the construction shown and described is merely illustrative, and that the same may be varied and modified and employed in other kinds of machines without departing from the spirit of the invention, and all changes, variations and modifications are contemplated as fall within the scope of the claims appended hereto.

110

I claim:—

125

1. A stop motion including, in combination: lever 24; a tension lever; an oscillatable member having a cut-away portion normally holding one end of said lever 24 against movement, said member having an

130

arm by which it is moved; and spring-controlled means normally locked in inoperative position by said tension lever and adapted to be released when the tension on the tension lever increases beyond normal whereby said means engage and move the arm on said member to oscillate it, substantially as specified.

2. A stop motion including, in combination: a lever 24; a tension lever; a take-up lever; an oscillatable hub having a cut-away portion and normally holding said lever 24;

an arm 49 secured to said hub; means intermediate the tension lever and said arm 49 adapted to be released when the tension increases beyond normal to thereby operate said arm 49; and means for moving said tension lever to operate the said arm 49 when the thread breaks, substantially as specified. 15
